UNITED STATES PATENT OFFICE.

FRITZ KEMPTER, OF STUTTGART, GERMANY.

AIR ACCUMULATOR.

Application filed October 8, 1920. Serial No. 415,690.

To all whom it may concern:

Be it known that I, FRITZ KEMPTER, a citizen of the German Empire, residing at Stuttgart, Germany, have invented certain 5 new and useful Improvements in Air Accumulators, of which the following is a specification.

My invention relates to air accumulators and its particular object is an automatic 10 starting and stopping device for such accumulators. In accumulators of this kind having a piston interposed and separating the compressed air from the pressure fluid, the control devices serving to automatically 15 govern the supply of the pressure fluid were hitherto operated either by means of compressed air with the separating piston freely suspended between this latter and the pressure fluid, in that the fluctuations of 20 pressure provoked by the reciprocating motion of said piston were caused to act on an electrical contact manometer which then in turn affected the respective devices, or by means of a rigid connection of the separating 25 piston with a piston rod passing either through the cover or the bottom of the accumulator cylinder, such rod equalling in length the piston stroke, and which set the respective devices in operation.

Now these aforesaid two control arrangements embody numerous drawbacks.

Thus in the first case there prevails the disadvantage that along with the unavoidable loss of compressed air during service 35 in consequence of leakage, the tension of said air comes to be altered and that in connection herewith the upper and lower terminal position of the separating piston—which cannot be observed from the outside—will undergo a corresponding change 40 on the contact manometer effecting the reversal which will then give rise to trouble.

In the second case, it is true, the control action is independent of the air pressure, 45 but in return the guide rod articulated to the separating piston increases the height of the accumulator structure, while the stuffing box, through which the piston rod has to be passed either in the cover or the 50 bottom of the accumulator cylinder, is exposed to much wear and consequently liable to frequent leakage, as the piston-rod is obliged to take part in even the slightest motion executed by the separating piston.

It is an object of my invention to obviate 55 these drawbacks by the reversal being

carried out generically speaking and indeed even as in the second case, by the separating piston, while at the same time omitting the long piston-rod hitherto required to this end and yet retaining the arrangement according to which the separating piston is freely suspended between the parts. In the place of the piston-rod, there is arranged either in the top or the bottom of the 60 accumulator cylinder, a short rod, the length of which does not correspond to the extent of the piston stroke but merely to the magnitude of the control motion, 65 said rod being acted on by the piston only periodically, i. e. only then, when the piston almost comes to assume its extreme position, while this rod is completely motionless for as long as the separating piston 70 happens to be in the opposite portion of 75 the accumulator-cylinder.

In the drawings affixed to this specification and forming part thereof, two accumulators embodying my invention are 80 illustrated by way of example. In the drawings

Fig. 1 is a vertical section through an accumulator, showing the control means.

Fig. 2 a similar view of a modified form,

Fig. 3 a cross sectional view of the construction according to Fig. 1, and

Fig. 4 is a cross-section of the valve connected with the accumulator shown in Figs. 1 and 3.

Referring to Fig. 1 of the drawings the rod 1, extending into the accumulator cylinder, is adapted to support the weight 5 suspended to the cross member 2 by the intervention of the rods 3 and 4. At its lowermost end the rod 3 supports the arm 6 adapted to slide along the rod 9 provided, for its part, with an adjusting collar 7. This rod 9 is articulated to the lever 10 of the by-pass valve 22. The lever 10 places itself above the casing 11 of valve; its fulcrum is indicated at 12, and it lifts the valve 22 from its seat 21 as soon as the rod 9 is raised. Whenever this is the case, the pawl 13 lodges itself underneath lever 10 and thereby secures it in its position. On the other hand, as soon as the weight 5 assumes its lowermost position, the pin 14 arranged on arm 6 strikes against the arm 15 of the lever and by these means releases the pawl; whereupon the lever 10 returns into its initial position and valve 22 again closes. The pipe 16 and 17 arranged on

either side of the valve casing, serve, respectively, for conducting the pressure fluid from and again back to the pump.

The manner of operation is as follows:

- 5 As soon as the separating piston is forced by the pressure fluid which enters the cylinder through pipe 19 and escapes through pipe 20 against the rod 1, it takes this latter along while continuing to rise until the arm 10 of rod 3 comes to abut against the collar 7 on rod 9 and draws this latter upward. By these means, the lever 10 in turn is lifted and secured in its raised position by the interposition of the pawl 13. The lever 15 10 being raised, the by-pass valve 22 comes to be opened so that now the action of the pressure pump is annihilated, that is to say, the pressure fluid is no longer fed into the accumulator but returned without pressure 20 to the pump barrel. At the same time, the accumulator is completely charged. If now pressure fluid be withdrawn from the accumulator, then the separating piston and with it the weight 5 will drop, valve 22 for the 25 present remaining unaffected. No sooner, however, does the pin 14 arranged on arm 6—after effecting a certain lost motion—come to attain the lever 15 when, and as the movement continues, the pawl 13 is released 30 and therewith valve 22 disengaged so that it may now close, whereupon the pump again commences to feed the accumulator. The aforesaid idle motion, which may be regulated at pleasure, is in so far of great importance as it will serve, for example in 35 the case of by-pass of the kind specified, to prevent any liability on the part of these latter to pound, which might otherwise be apt to occur where the supply and consumption 40 of the pressure fluid are approximately the same and where the separating piston tends to oscillate when in its uppermost position.

It will thus be seen that by means of the 45 improved construction there is produced a self-acting device adapted to cut off the pressure fluid supply of the accumulator by the aforesaid or any other suitable means, and then again to open the supply and this 50 either sooner or later according to the position assumed by the piston within the working cylinder and the length of rod 1.

In the modified form disclosed by Fig. 2, the pressure fluid is located beneath and 55 the compressed air above the piston, while the cylinder is lodged on a raised pedestal in which the by-pass valve 11 is arranged. This valve protrudes by means of an extension rod 1 passing through the cylinder

cover into the cylinder and is kept closed 60 by the intervention of a spring 18. The feed pipe 16 serves to establish communication between the pump and the accumulator, while pipe 17 serves for the return to the pump barrel. On the by-pass valve being 65 closed, the connection established by pipes 16 and 17 is cut.

As soon as the piston depresses the rod 1, the said valve is opened, pipes 16 and 17 enter into action again, and the fluid supplied by the pump is again caused to flow back into the pump barrel. 70

By suitable provision, the adjustable lost motion described in connection with the construction according to Fig. 1, may also 75 be introduced into the modified construction according to Fig. 2.

I claim:

1. In a device of the kind described in combination, a cylinder closed at both ends, a rod-less piston freely movable within said cylinder, means comprising a valve for introducing a pressure liquid at one end of said cylinder and a rod operatively connected with said valve projecting into said cylinder so as to be acted upon by said piston at one end of its stroke. 80 85

2. In a device of the kind described in combination, a cylinder closed at both ends, a piston freely movable within said cylinder, means comprising a valve for introducing a pressure liquid at one end of said cylinder, a rod projecting into the other end of said cylinder so as to be acted upon by said piston at the end of its stroke and a connection between said rod and said valve adapted to cause said valve to be reversed upon the rod having been displaced a certain distance by said piston. 90 95

3. In a device of the kind described in combination, a cylinder closed at both ends, a piston freely movable within said cylinder, means comprising a valve for introducing a pressure liquid at one end of said cylinder, a rod projecting into the other end of said cylinder so as to be acted upon by said piston at the end of its stroke, a second rod connected with said first rod and adapted to move into operative contact with said valve, a weighted lever for locking said valve in a certain working condition and means, adapted to be actuated by said second rod on the first rod having been displaced a certain distance by said piston, for releasing said locking lever. 100 105 110

In testimony whereof I affix my signature.

FRITZ KEMPTER.
